UNITED STATES PATENT OFFICE.

MORRIS L. ORUM, OF PHILADELPHIA, PENNSYLVANIA.

GAGE-SLIDE FOR ROTARY CUTTERS.

SPECIFICATION forming part of Letters Patent No. 278,815, dated June 5, 1883.

Application filed January 9, 1883. (No model.)

To all whom it may concern:

Be it known that I, MORRIS L. ORUM, of the city and county of Philadelphia, in the State of Pennsylvania, have invented certain new and useful Improvements in Gage-Slides for Rotary Cutters, of which improvements the following is a specification.

The object of my invention is to provide means for presenting stock to the action of a rotary cutter or laterally-cutting bit in such manner as to insure the formation of a recess of any desired extent, and to prevent the splitting of the wood by the cutter on the exit side of its cut.

To these ends my improvements consist in the combination of a sliding frame or rest and a gage having a recess corresponding in form and dimensions with the axial sectional outline of the cutter; also, in the combination of a gage-slide having a recess which is a counterpart of the axial sectional outline of a rotary cutter, and a fixed stop adapted to abut against the side of the gage opposite to that against which the stock to be cut rests.

The improvements claimed are hereinafter more fully set forth.

In the accompanying drawings, Figure 1 is a view in perspective of a gage-slide embodying my invention; Fig. 2, a transverse section 30 through the same at the line $x-x$ of Fig. 3; Fig. 3, a plan or top view of the same; and Fig. 4, a view in perspective, illustrating the character of the recess made by a cutter in connection with which the gage-slide is designed to operate.

To carry out my invention I provide a frame, A, which is secured to the table A' of a dovetailing or recessing machine, in which a rotary cutter or laterally-cutting bit, a, is secured 40 upon and rotates with a vertical shaft, a'. A rest, B, upon which the stock or stuff to be cut is placed, is fitted to slide between the side bars of the frame A toward and from the cutter a. A transverse bar or bridge-piece, B', is secured 45 to the rest B at the end adjacent to the cutter, and is recessed or curved upwardly at its center, so as to pass freely by the same. A gage, B², against which the stock abuts, is secured to the bar B', its lower edge being flush with 50 or slightly below the bottom of the cutter-head, and a recess, b, which is, as nearly as may be, a counterpart of the axial sectional outline of

the cutter, is formed in the gage in line with the axis of the cutter-shaft. Said recess admits of the gage being moved up to and past the cutter, while presenting a bearing-surface for the stock for the entire extent of the cutting-edges. The position of the stock is regulated laterally by a stop, b', which is adjustable toward and from the recess b by a set-screw, b², 60 working in a slot in the gage. A lever, C, pivoted to the bar B', serves, when swung downward, to hold the stock in position upon the rest, as well as to move the rest and the stock placed thereon to and from the cutter. 65

It will be obvious that, if desired, the bar B' might be dispensed with and the lever C be pivoted directly to the gage B²; but, inasmuch as a special gage is required for and in conformity with each of the different sizes and 70 forms of cutters employed, I prefer to make the gage a separate piece, and to form it of wood, so that the recess b may be accurately made by the particular cutter with which it is designed to operate, and any injury to the cutter 75 by lateral movement of the gage be obviated.

The longitudinal extent of the cut to be made in the stock is regulated, as desired, by a stop, D, secured to the frame A at the end opposite that from which the stock is fed, said stop being adjustable for greater or less lengths of cut, and being formed in this instance of a set-screw having a clamping-nut, d.

In operation, the rest and gage being on the right-hand side of the cutter, the stock or block 85 of stuff, E, which is to be cut, is placed upon the rest with its side, e, in which the cut is to commence abutting against the gage B², and one of its sides at right angles thereto abutting against the lateral stop b'. It is then 90 clamped in position by the lever C, and the cutter a being rotated at a proper speed, the rest is pushed toward the cutter until arrested by the stop D, when it is withdrawn and the stock, in which a recess, e', has been formed, 95 is removed. Inasmuch as the gage B² bears against the stock entirely up to and along the edges of the cutter, the ordinary tendency of the latter to split the wood on the exit side of the cut is obviated, and by the adjustment of 100 the stop D the extent of each cut made is regulated to the exact length desired.

I am aware that a sliding bed adapted to support and feed stuff to a rotary cutter was

known at the date of my invention, and such, therefore, I do not broadly claim.

I claim as my invention and desire to secure by Letters Patent—

- 5 1. The combination, substantially as set forth, of a sliding frame or rest and a gage having a recess which conforms substantially to the axial sectional outline of a rotary cutter, these members being combined for joint operation to afford a support for the stuff entirely up to and along the edges of said cutter.
- 10 2. The combination, substantially as set forth, of a sliding frame or rest, a gage secured thereto and recessed conformably with the axial sectional outline of a rotary cutter, and a fixed stop.
- 15

3. The combination, with a rotary cutter, of a sliding frame or rest, a gage secured thereto and recessed conformably with the axial sectional outline of said cutter, a clamping-lever 20 pivoted thereto, and a stop fixed with the capacity of adjustment toward and from the cutter to the table thereof on the side opposite that from which the stock is fed, substantially as set forth.

MORRIS L. ORUM.
